COMBINED BILLIARD TABLE AND EXPANDING TABLE

Rudolf Roch and Henry Roch,
Dresden, GermanyApplication August 27, 1934, Serial No. 741,599
In Germany August 28, 1933

5 Claims. (Cl. 273—4)

Our invention relates to a combined billiard and expanding table. The object is to encourage the game of billiards in homes where there is not sufficient space available for a separate billiard table.

The present invention consists in a combined billiard and expanding table in which the billiard table bed is normally concealed beneath a divided horizontally expanding removable table top and is mounted within the frame of the table, so that the table can be used as such with the top either expanded or closed while upon the table top being entirely removed, the table can be used as a billiard table.

The table top consists of horizontally extensible sections between which removable leaves may be placed to increase the size of the table surface.

The bed of the billiard table is built into the frame of the table proper, and the frame is finished off flat all round on the top so that it forms the outer frame of the billiard table. Rails are let into the flat top of the frame lengthwise, and these rails each consist of two telescoping parts, one of which is fixed to the frame and the other to one of the tops of the table, at the same time reinforcing said top. The billiard table bed is sunk beneath the flat top of the outer frame between the side rails. The billiard table cushions are secured within the outer frame and rest on the billiard table bed. The bed of the billiard table provides a space in which the accessories of the game can be placed, such as cues, balls, etc. There may however be also provided a special drawer beneath the billiard table bed to receive these accessories. A combined expanding and billiard table is thus provided which can be produced very cheaply.

On the accompanying drawing showing by way of illustration an embodiment of the present invention:—

Figs. 1 and 2 are respectively a side and end view of the table.

Fig. 3 is a top plan view of the extended table with two extra leaves inserted.

Fig. 4 is a top plan view of the table when used as a billiard table.

Figs. 5 and 6 are detail sectional views of two different constructions drawn to a larger scale.

The expanding table may be of any suitable size. As shown it comprises legs 1, longitudinal members 2a and transverse members 2b, upon which is secured a flat frame consisting of longitudinal bars 3a and cross bars 3b. Let into the two longitudinal bars 3a are rails 4 each made in two telescoping parts 4a and 4b. The part 4a

is fixed to the longitudinal bar 3a and the part 4b to one of the sections 5 of the table top. The rails 4 are such that each top section 5 can be drawn off entirely from one end of the table when the table is to be used for the game of billiards as shown in Fig. 4. The top sections 5 can also be partly extended as in Fig. 3 so that one or more separate leaves 6 can be inserted between them. The billiard table cushion strips 7 are secured to the flat frame bars 3a and 3b and rest on the bed 8 of the billiard table. In the space 8 below the table top, cues, balls and the like can be stored. The bed 8 is preferably a five-ply glued and impregnated board of batten wood, but may be made of any other material, and may be secured to filling pieces 8a.

The rails 4, being sunk within the frame bars 3a, do not interfere with play on the billiard table. They can be constructed in any suitable manner, for example according to either Fig. 5 or Fig. 6, and the groove through which the guides of the top sections pass can be made very narrow as shown in Fig. 6.

Spring bolts or spring locks 10 may be provided at both ends of the frame, on the bars 3b to engage corresponding holes or recesses 10a, 10b and 10c in the underside of the table leaves 5, so that the top sections can be locked in either of the positions shown in Fig. 1 and Fig. 3 or in an intermediate position when only one extra leaf 6 is inserted between the two tops 5.

It is to be understood that the invention is not limited to the particular construction herein described and shown in the drawing.

We claim:

1. A combination extension and billiard table, comprising a frame, legs supporting said frame, a billiard bed supported by said frame in a plane below the same, guiding means provided in said frame, and a divided table top composed of removable sections in sliding engagement with said guiding means for horizontal inward and outward displacement.

2. A combination extension and billiard table, comprising a frame, legs supporting said frame, a billiard bed supported by said frame in a plane below the same, guide rails provided in said frame, removable table top sections provided on their undersides with parts for telescopic engagement with said guide rails, and table leaves adapted to be inserted intermediate said top sections.

3. A combination extension and billiard table, comprising a frame, legs supporting said frame, a billiard bed supported by said frame in a plane below the same, guide rails provided in said

frame, removable table top sections provided on their undersides with parts for telescopic engagement with said guide rails, and table leaves adapted to be inserted intermediate said top sections, and elastic locking means on said frame for locking said top sections in position.

4. A combination extension and billiard table, comprising a flat frame composed of longitudinal and transverse members and supported on legs, a billiard bed secured to said members in a plane below the frame, guide-rails provided in grooves of said longitudinal members, and removable table top sections provided on their underside with means telescopically engaging said guide-rails so as to be moved inwards and outwards horizontally.

5. A combination extension and billiard table, comprising a flat frame composed of longitudinal and transverse members and supported on legs, a billiard bed secured to said members in a plane below the frame, guide-rails provided in grooves of said longitudinal members, and removable table top sections provided on their underside with means telescopically engaging said guide-rails so as to be moved inwards and outwards horizontally, and cushions for said billiard bed secured to said longitudinal and transverse members in contact with said bed. 5 10 15
